(57) CLAIM

The ornamental design for a taco holder, as shown and described.

DESCRIPTION

FIG. 1 is a top view of a taco holder in an unfolded configuration incorporating my new design;

FIG. 2 is a bottom view thereof;

FIG. 3 is a left side view thereof;

FIG. 4 is a right side view thereof;

FIG. 5 is a front view thereof;

FIG. 6 is a rear view thereof;

FIG. 6 is a bottom view thereof.

FIG. 7 is a top perspective view of the taco holder in a folded configuration;

FIG. 8 is a right side view thereof;

FIG. 9 is a left side view thereof;

FIG. 10 is a front view thereof;

FIG. 11 is a rear view thereof;

FIG. 12 is a top view thereof; and,

FIG. 13 is a bottom view thereof.

The broken lines in the drawings depict portions of the taco holder that form no part of the claim.
